(57) **CLAIM**

The ornamental design for a toilet seat for children, as shown and described.

DESCRIPTION

FIG. 1 is a top, front, right side perspective view of a toilet seat for children, showing my new design;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labelled 9 in FIG. 1;

FIG. 10 is an enlarged view of a portion labelled 10 in FIG. 1;

FIG. 11 is an enlarged view of a portion labelled 11 in FIG. 1;

FIG. 12 is an enlarged view of a portion labelled 12 in FIG. 1;

FIG. 13 is an enlarged view of a portion labelled 13 in FIG. 2;

FIG. 14 is an enlarged view of a portion labelled 14 in FIG. 2;

FIG. 15 is an enlarged view of a portion labelled 15 in FIG. 2;

FIG. 16 is an enlarged view of a portion labelled 16 in FIG. 3;

FIG. 17 is an enlarged view of a portion labelled 17 in FIG. 4;

FIG. 18 is an enlarged view of a portion labelled 18 in FIG. 5;

FIG. 19 is an enlarged view of a portion labelled 19 in FIG. 6;

FIG. 20 is an enlarged view of a portion labelled 20 in FIG. 7; and,

FIG. 21 is an enlarged view of a portion labelled 21 in FIG. 7.

The broken lines in the drawings depict portions of the toilet seat for children that form no part of the claimed design.

The dash dot dash lines in FIG. 1, FIG. 2, FIG. 3, FIG. 4,

FIG. 5, FIG. 6, FIG. 7, FIG. 9, FIG. 10, FIG. 11, FIG. 12,

FIG. 13, FIG. 14, FIG. 15, FIG. 16, FIG. 17, FIG. 18, FIG.

(Continued)

19, FIG. 20 and FIG. 21 are for the purpose of depicting the cut line of the enlarged view and no part of the claim.

1 Claim, 21 Drawing Sheets
